(57) **CLAIM**

The ornamental design for a flexible garment insert, as shown and described.

DESCRIPTION

FIG. 1 is an isometric view of the claimed flexible garment insert showing the convex outer surface, embodying the present design;

FIG. 2 is an isometric view of the claimed flexible garment insert showing the concave inner surface, embodying the present design;

FIG. 3 is a front side view thereof, showing the convex outer surface;

FIG. 4 is a rear side view thereof, showing the concave inner surface;

FIG. 5 is a side view thereof, with the convex outer surface facing downward;

FIG. 6 is a side view thereof, with the convex outer surface facing upward;

FIG. 7 is a top down plan view thereof; and,

FIG. 8 is a bottom up plan view thereof.

1 Claim, 8 Drawing Sheets
